UNITED STATES PATENT OFFICE

FRANK C. LAYER, OF ALGONQUIN, ILLINOIS

BRICK HACKING APPARATUS

Application filed May 20, 1931. Serial No. 538,768.

My present invention relates to brick handling apparatus, and more particularly to a novel and improved brick hacking apparatus.

An important object of the present invention is the provision of novel apparatus by means of which brick may be stacked in a hack on a car or truck for delivery to a drier or kiln, in predetermined and prearranged formation for subsequent handling in the kiln shed by lifting forks or other devices to handle the entire truck load as a unit.

Another object of the invention resides in considerably lessening the time required to load the aforesaid cars or trucks for delivery to the kiln.

Another object of the invention resides in a substantial reduction in the labor personnel heretofore required to carry out this transfer operation.

Another object of my invention resides in the provision of a plurality of grouping frames, conveyed throughout my novel apparatus in predetermined sequence, so that a predetermined number of frames will complete one cycle of operation of the apparatus, and on the completion of said cycle, a car or truck will have been completely loaded, ready for delivery to the kiln.

Another object of the invention resides in so constructing and arranging the aforesaid grouping frames that the bricks placed therein will be in a position for deposit upon the delivery truck in prearranged relation, not only with the brick in a given course, but also with the bricks in adjacent courses.

A still further object of the present invention resides in the provision of novel carriers for transporting the loaded grouping frames from one station to another.

A further object of the invention resides in a novel track arrangement for conducting the aforesaid carriers from one station to another, coupled with reversing means to reverse the direction of travel of said carriers, to return them to the initial frame receiving position.

Another feature of my invention resides in the arrangement of conveyors utilized in cooperation with the said track mechanism and carriers transported thereon.

In carrying out my invention my novel apparatus is arranged in substantially rectangular form, comprising a cross conveyor by means of which empty grouping frames are delivered in position to be received by the carriers, a second conveyor conducting brick from any desired point, as for example from a drier, to said cross conveyor, at which point they are diverted and fed into the compartments of the grouping frames. The carriers above mentioned clamp a filled grouping frame, and convey the same to a station beneath which is located a car or truck. At this station the grouping frame is released, said frame and the bricks carried thereby being positioned in proper relation on said truck. Thereupon the grouping frame is removed from the brick, placed on a gravity conveyor, and automatically fed to an endless conveyor which in turn feeds the empty grouping frames to the first cross conveyor, at which point they are placed on said conveyor in proper position. After a carrier has released its grouping frame and the brick carried thereby, it continues its travel along its track, until the end thereof is reached, at which point means is provided to automatically reverse the direction of travel of said carrier. Thereupon the carrier will return, on a parallel track, to the other end of the track system, at which point means is provided to again automatically reverse the direction of travel of said carrier, and the said carrier will thereupon be automatically forwarded to the point or station prepared to clamp another filled grouping frame.

Other objects of my invention reside in the particular construction and arrangement of the parts of my novel apparatus, and all of the above, together with other objects and features of the invention, details of construction, combinations of parts, and advantages, will be hereinafter more fully pointed out, described and claimed.

I believe that the apparatus herein illustrated and described is novel, and have therefore claimed the same broadly in the present application.

I also believe that the system of hacking

brick, by means of prearranged grouping frames, is novel, and have therefore claimed said system in this application.

Referring to the drawings, illustrating a preferred embodiment of the present invention,

Figs. 1 and 2 constitute a plan view of my novel apparatus;

Fig. 3 is a vertical sectional view on the line 3—3 of Fig. 1;

Fig. 4 is a vertical sectional view on the line 4—4 of Fig. 3;

Fig. 5 is an enlarged cross sectional detail of a grouping frame in brick receiving position on the cross conveyor;

Fig. 6 is a plan view of one of the carriers;

Fig. 7 is a vertical sectional view on the line 7—7 of Fig. 8;

Fig. 8 is a vertical sectional view on the line 8—8 of Fig. 7;

Fig. 9 is a side elevation illustrating the loading of a truck;

Fig. 10 is an end elevation of said truck during the loading operation;

Fig. 11 is a top plan view illustrating the turntable on the transfer car, and the truck to which the filled cars are conveyed for delivery to the kiln;

Fig. 12 is a vertical sectional view on the line 12—12 of Fig. 2;

Fig. 13 is a vertical sectional view on the line 13—13 of Fig. 12;

Fig. 14 is an enlarged fragmentary perspective detail of the pivoted live rail joint;

Fig. 15 is an enlarged fragmentary cross sectional view on the line 15—15 of Fig. 8;

Fig. 16 is a wiring diagram of the entire system; and

Fig. 17 is a wiring diagram of the carrier.

Referring now to the drawings, for a particular description of the invention, its construction and operation, 10 designates a conveyor, such as a belt conveyor, driven by a shaft 11 which in turn is rotated by a chain 12 connected to the shaft 13 of a motor 14, a switch 15 being provided to stop and start the conveyor 10 at will. This conveyor 10 is adapted to transport bricks 16, preferably arranged longitudinally of the belt, in pairs.

50. The conveyor 10 extends from the usual cutting table and the brick, when placed on the cars, will be delivered to a drier in which the green brick are dried preparatory to their being burned in a suitable kiln.

55. The conveyor 10 terminates closely adjacent to a cross conveyor 17, this cross conveyor comprising the belt 17 supported on a plurality of rolls 18 throughout a portion of its length, the rolls 18 being supported on shafts 19 in a suitable frame 2. The belt 17 is endless, and is driven by means of a motor 21, the operation of this cross conveyor 17 being continuous, except as herein-after explained. Fixed to the belt 17, as by 60. rivets 22, are a plurality of channel irons 23,

certain of these channel irons projecting above the other, as at 24, and being provided with shoulders 25. Mounted in the channel irons 23 are a plurality of shafts 26 carrying rollers 27 extending longitudinally of the conveyor 17.

A plurality of grouping frames are provided, these grouping frames being divided into three classes, here illustrated as 28, 29 and 30. These frames are placed upon the cross conveyor 17 in a manner to be herein-after more fully described, and are fed by the conveyor laterally across the end of the conveyor 10. Adjacent to the end of the conveyor 10, on a platform 31, stands an operator, here designated as 1. This operator transfers the bricks 16 from the conveyor 10 into the chambers of the conveyors, sliding the brick 16 laterally of the conveyor 17 across the rolls 27, these rolls 27 facilitating the feeding of the brick 16 into the grouping frames. A stop plate 32 is provided, against which the brick 16 will abut when being fed into the grouping frames. The grouping frames 28 are utilized in laying finger courses on a car, as will be herein-after more fully explained, and are each adapted to carry sixteen brick, with the exception of the finger course grouping frames designated at 33, which are adapted to carry twenty-four brick each.

As will be clearly apparent from an inspection of Fig. 3, the grouping frames rest on the shoulders 25, being confined between the raised portions 24 of the channel irons 23. The filled grouping frames are carried by the conveyor 17 to a position beneath a carrier designated generally at 34.

The carrier 34 rides on wheels 35 on tracks 36, longitudinal beams 37 being provided to support a motor 38, as well as the supporting members 39, on the upper end of which are slidably mounted side frames 40. Depending from the side frames 40 are clamping irons 41, normally held in separated position by means of U-shaped leaf springs 42 bearing against the clamping members or arms 41.

Mounted on one side frame 40 is a crank 43 rotating a pulley 44 to which is fixed a cable 45. This cable 45 surrounds an idler pulley 46 mounted on the opposite side frame 40, and is returned and fixed to a post 47 on the first side frame 40. Thus, rotation of the crank 43 in a counter-clockwise direction, as viewed in Fig. 6, will effect a drawing together of the side frames 40, sliding on the members 39 by means of the slots 48 and pins 49. This drawing together of the side frames 40 will also draw the clamping arms 41 together, clamping the same against the outside of a grouping frame, as for example the frame 29 illustrated in Fig. 3, securely clamping the brick 16 within said frame. The clamping of the brick is permitted because

of the fact that the partitions 50 are slideable upon shafts 51, spacing sleeves 52 being provided, as clearly illustrated in Fig. 5. The carrier 34 is now ready to be conveyed along 5 its tracks 36 to the delivery station for the grouping frames.

Carried by the side frames 53 is a live rail 54 adapted to be engaged by the brushes 55 on the carrier 34. Current is conducted 10 from the brushes 55 through wires 56 to the motor 38, through the medium of current conducting terminals 57, fixed on a bracket 58, said bracket in turn being fixed to one of the cross beams 37, as clearly shown in Fig. 6. 15 When the carrier 34 is in the position illustrated in Fig. 1, it is in a dead spot, it being noted that the live rail 54 terminates before reaching the cross conveyor 17. When the crank 43 has been operated to clamp a filled 20 grouping frame in the carrier 34, the operator 2 pushes the carrier 34 along its tracks 36 until it brushes 55 are in contact with the live rail 54, said brush being forced against said rail 54 by a coiled spring 59 bearing 25 against the insulating block 60, said spring 59 surrounding a stem 61 and a nut 62 limiting outward movement of the block 60.

When the operator 2 has pushed the filled 30 carrier 34 into contact with the live rail 54 he will operate the switch 63, thus preparing the car for travel along its tracks 36 when another operator, designated as 3, has closed the switch 64.

Assuming that the operator 3 has closed 35 the switch 64, the filled carrier will then travel along its tracks 36 until it reaches the rear spot adjacent to the switch 64, in Fig. 2, where it will be noted that there is a break in the live rail 54 similar to the break illustrated in Fig. 1. Motion is imparted to the 40 carrier 34 by means of the motor pinion 65 rotating a gear 66 which in turn rotates a shaft 67 carrying a sprocket 68 by means of which a chain 69 will rotate the axle 70 and 45 hence the wheels 35 fixed thereto.

Thus, so long as current is conveyed from the live rail 54 to the motor 38, the carrier will travel along its tracks 36. When the filled conveyor reaches the dead spot adjacent 50 to the operator 3, said operator will spot the carrier at any point desired over a car 71, and will thereupon rotate the crank 43 to permit the springs 42 to separate the side frames 40 and release the clamping arms 41 over the grouping frame carried thereby, thereupon releasing the grouping frame and the bricks carried thereby upon the car 71 or upon the course or courses of brick theretofore laid on said car. Thereupon an operator 55 designated as 4 removes the grouping frame from its brick and places said frame upon a gravity conveyor designated generally at 72. After the operator 4 has removed the empty grouping frame, the operator 3 60 will push the empty carrier 34 along its

tracks 36 until it is again in engagement with the live rail 54, whereupon said operator will close the switch 64 and again energize the entire system, with the exception of the conveyor 10, which is operated solely by the 70 operator 1.

On closing of the circuit, by means of the switch 64, all of the carriers, except those within the two dead spots above mentioned, will be set in motion, as well as the cross conveyor 17, and the longitudinal conveyor 73, to which the empty grouping frames are delivered by the gravity conveyor 72. The conveyor 73 is operated by a motor 74, chain 75, and shaft 76, and said conveyor 73 will 75 transport the empty grouping frames back to the cross conveyor 17, terminating just short thereof. At this point is stationed an operator 5, who will take the empty grouping frames from the conveyor 73 and place 80 them in proper position on the cross conveyor 17.

After a car has left the dead spot adjacent to the operator 3, and is again energized, it will strike a gate 77, carrying track sections 36 coinciding with the main tracks 36, and will move said gate to the position illustrated in dotted lines in Fig. 2, the carrier continuing in its travel until it reaches the end of its tracks 36 at the left of Fig. 2. As it reaches this point, a striker 78 will engage the lug 79 on the lever 80, this lever 80 being provided with a pair of arcuate slots 81 within which ride the pins 82 fixed to the live rail sections 83 and 84 respectively. Engagement of the lug 79 by the striker 78 will rock the lever 80 on its pivot 85, throwing the live rail section 83 out of contact with the brushes 55, and moving the live rail section 84 into contact with the brushes 55 on the opposite side of said carrier. The last slight forward travel of the carrier will cause the rod 86 to strike the bumper 87, and this will slide the rod 86 through its bearings 88, removing the current conducting contacts 89 from the terminals 57 and transferring the same to the terminals 90, resulting in a reversal of rotation of the motor 38, and hence a reversal of travel of the carrier 34.

The gate 77 is pivoted on a vertical shaft 91, and is moved by the carrier 34 in its forward movement against a counter-weight 92, said counter-weight being connected to the gate 77 by a cable 93 passing over the pulleys 94. As soon as the carrier 34 has passed the gate 77, the counter-weight will draw the same back to its normal position, or to the position illustrated in full lines in Fig. 2, permitting the carrier to be switched to the outside tracks 95, with the opposite brushes 55 in engagement with the live rail 107, for return to loading position. As the carrier 34 returns, or is reversed, a striker 96 will engage the outer end of a lever 97, pivoted at 98, and connected to the lever 80 by a rod 99, 130

thus rocking the lever 80 on its pivot 85 and returning the same to the normal position illustrated in Fig. 2, together with the live rail sections 83 and 84.

- 5 When the empty carrier 34 approaches the end of the tracks 95 adjacent to the loading station, it will engage a gate 100, similar to the gate 77, and will swing the same to permit the carrier to ride on to the first tracks 36.
- 10 This end of the tracks 36 is also provided with a lever 101, similar in each respect with the lever 80, operating the live rail sections 102 and 103 exactly the same as the sections 83 and 84.
- 15 As the empty carrier reaches the end of its reverse travel, the rod 86 will strike the bumper 104, moving the contact points 89 back to the position illustrated in Fig. 6, for forward travel of the carrier 34. Movement 20 of the rod 86 in each direction, and correct positioning of the contact points 89 relative to the terminals 57 and 90 is controlled by the collars 138. This forward travel will continue as long as the circuit is closed. As 25 the carrier 34 starts again on its traverse of its tracks 36, the striker 96 on the opposite side of the car will engage the lever 105, and operate the rod 106 to pivot the lever 101 and return the same, together with the live rail 30 sections 102 and 103, to normal position, as illustrated in full lines at the right-hand side of Fig. 1. The carrier 34 will then continue its forward travel until it reaches the dead spot adjacent to the operator 2. These 35 dead spots adjacent to the operators 2 and 3 are of sufficient extent to accommodate any desired number of cars at a time, being here illustrated as sufficient to carry or accommodate two carriers 34.
- 40 Beneath the dead spot adjacent to the operators 3 and 4 is a pit 108, in which tracks 109 are fixed on a suitable bed 110, a transfer car 111 riding on the rails 109. The top of the transfer car is rotatable relative to the 45 base thereof, and this turntable top designated generally at 112, carries angularly arranged sets of tracks 113 and 114, adapted to register, at predetermined intervals, with the incoming tracks 115 and the outgoing 50 tracks 116.

The car 71 is provided with wheels 117 adapted to ride on the rails 114 and 113 respectively. The car 71 is provided with a vertically movable bed 118, to which are fixed 55 cables 119, these cables being fixed to drums 120 on a shaft 121, and other cables 122 being united to drums 123 on the shaft 121 and passing around idlers 124 on the shaft 125, whence said cables 122 extend to the other 60 end of the car and pass around idlers 126 and 127, whence they are again fixed to the deck of the car.

65 Fixed to the shaft 121 is a crank 128 and ratchet 129, said ratchet being in engagement with a pawl 130. When an empty car 71 is

positioned on the transfer car 111, the deck 118 is raised to the top of the car 71, so that the first grouping frames and their brick are deposited directly on the deck 118.

70 As illustrated in Figs. 9 and 10, the first brick deposited are in finger courses, with spaces 131 between groups of bricks to permit the entrance of the fingers of lifting forks, or other devices. When two tiers of finger courses have been laid, the operator 75 designated at 6 then swings the car 71 at right angles to its original position, whereupon a stretcher course is laid. Thereupon the operator 6 again swings the car 71 at right angles, and a header course is laid.

80 In Fig. 9 the apparatus is illustrated as laying a stretcher course, as will be readily understood.

85 As each course is completed, the operator 6 manipulates the crank 128 and lowers the deck 118 a predetermined distance, equivalent to the height of one course, and determined by the distance between the teeth on the ratchet 129, being held in adjusted position by the pawl 130. The tracks 36 are inclined upwardly, from adjacent to the dead spot to the end thereof, so that the conveyor 72 will have a sufficient incline to insure a gravity feeding of the empty grouping frames to the longitudinal conveyor 73.

90 After the car 71 has been loaded, it is then pushed from the transfer car 11 over the tracks 116 on to a truck 132 provided with sets of tracks 133, the truck 132 being of sufficient size to accommodate three cars 71, although it will be appreciated that this is for 100 illustrative purposes only. The truck 132 is mounted on tracks 134 which preferably run directly into the drier or kiln shed, whence the cars 71 are conducted for unloading by any suitable unloading, handling, or lifting forks or devices.

105 The operator 3 stands on a scaffold 135, rotatably mounted on a pivot 136, a ladder 137 being provided for access to said scaffold. Thus the operator 3 may shift the position 110 of the scaffold 135 to coincide with the position of the carriers 34 or the car 71, as desired.

115 In order to completely load the car 71, I find that thirty-nine grouping frames are required. Thus, when the last grouping frame has been deposited on the car 71, a cycle is completed, and the first grouping frame of the next cycle will be carried by the next carrier conveyed to the operator 3, it being necessary to position a new car 71 on the transfer car 111, with the deck 118 raised to its uppermost limit, before commencing the loading of said new car 71.

120 By carrying out my novel system, with the grouping frames prearranged in correct rotation or sequence, loading or building of the 125 stack on the car 71 is facilitated, the operators having the correct grouping frames au- 130

tomatically positioned for release by the operator 3, and each successive grouping frame being placed on the conveyor 72 and delivered to the operator 5 for replacing on the 5 cross conveyor 17 in correct sequence and relation.

By the use of my novel apparatus I am enabled to effect the loading of a car 71 in but a fraction of the time heretofore required to 10 effect the building of a hack on such a car.

The advantages of my novel apparatus and system will be instantly apparent to those skilled in this art.

While I have necessarily described my 15 present invention somewhat in detail, it will be appreciated that I may vary the size, shape, and arrangement of parts, within reasonably wide limits without departing from the spirit of the invention.

20 My invention is further described and defined in the form of claims as follows:

1. Brick hacking apparatus of the kind described, comprising a car loading station, a set of brick holding grouping frames of varying 25 sizes and capacity, said set of frames representing the total volume of a car, and means to convey said frames to said car loading station in proper sequence.

2. Brick hacking apparatus of the kind described, comprising a car loading station, a set of brick holding grouping frames of varying sizes and capacity, said set of frames representing the total volume of a car, a loading 30 station for said frames, and means to 35 convey said frames to said car loading station in proper sequence.

3. Brick hacking apparatus of the kind described, comprising a car loading station, a set of brick holding grouping frames of varying 40 sizes and capacity, said set of frames representing the total volume of a car, a loading station for said frames, means to convey said frames to said car loading station in proper sequence, and means to return said 45 frames to said frame loading station.

4. Brick hacking apparatus of the kind described, comprising a set of tracks, a second set of tracks parallel with said first tracks and converging thereon adjacent to its ends, 50 electrically operated carriers on said tracks, means to automatically reverse the direction of movement of said carriers at the end of said first tracks, a loading station in said first tracks, an unloading station remote from said loading station, a plurality of grouping frames, a cross conveyor adapted to carry said frames to said loading station, and means on each of said carriers adapted to clamp a frame therein.

5. Brick hacking apparatus of the kind described, comprising a set of tracks, a second set of tracks parallel with said first tracks and converging thereon adjacent to its ends, electrically operated carriers on said 60 tracks, means to automatically reverse the direction of movement of said carriers at the end of said first tracks, a loading station in said first tracks, an unloading station remote from said loading station, a plurality of grouping frames, a cross conveyor adapted to carry said frames to said loading station, and means to operate said carriers and said conveyors in unison.

65 6. Brick hacking apparatus of the kind described, comprising a set of tracks, a sec-

direction of movement of said carriers at the end of said first tracks, a loading station in said first tracks, an unloading station remote from said loading station, a plurality of grouping frames, a cross conveyor adapted 70 to carry said frames to said loading station, and manually operated means on each of said carriers adapted to clamp a frame therein.

7. Brick hacking apparatus of the kind described, comprising a set of tracks, a second set of tracks parallel with said first tracks and converging thereon adjacent to its ends, electrically operated carriers on said tracks, means to automatically reverse the direction of movement of said carriers at the end of said first tracks, a loading station in said first tracks, an unloading station remote from said loading station, a plurality of grouping frames, a cross conveyor adapted 75 to carry said frames to said loading station, means on each of said carriers adapted to clamp a frame therein for transfer to said unloading station, and a conveyor adapted to return empty frames to said cross conveyor.

80 8. Brick hacking apparatus of the kind described, comprising a set of tracks, a second set of tracks parallel with said first tracks and converging thereon adjacent to its ends, electrically operated carriers on said tracks, means to automatically reverse the direction of movement of said carriers at the end of said first tracks, a loading station in said first tracks, an unloading station remote from said loading station, a plurality of grouping frames, a cross conveyor adapted 85 to carry said frames to said loading station, means on each of said carriers adapted to clamp a frame therein for transfer to said unloading station, a conveyor adapted to return empty frames to said cross conveyor, and a gravity conveyor interposed between said unloading station and said last named conveyor to automatically deliver said empty frames to said last named conveyor.

90 9. Brick hacking apparatus of the kind described, comprising a set of tracks, a second set of tracks parallel with said first tracks and converging thereon adjacent to its ends, electrically operated carriers on said tracks, means to automatically reverse the direction of movement of said carriers at the end of said first tracks, a loading station in said first tracks, an unloading station remote from said loading station, a plurality of grouping frames, a cross conveyor adapted 95 to carry said frames to said loading station, means on each of said carriers adapted to clamp a frame therein for transfer to said unloading station, a conveyor adapted to return empty frames to said cross conveyor, and means to operate said carriers and said conveyors in unison.

100 10. Brick hacking apparatus of the kind described, comprising a set of tracks, a sec-

ond set of tracks parallel with said first tracks and converging thereon adjacent to its ends, electrically operated carriers on said tracks, means to automatically reverse the direction of movement of said carriers at the end of said first tracks, a loading station in said first tracks, an unloading station remote from said loading station, a plurality of grouping frames, a cross conveyor adapted to carry said frames to said loading station, a brick carrying conveyor terminating adjacent to said cross conveyor, means on each of said carriers adapted to clamp a frame therein for transfer to said unloading station, a conveyor adapted to return empty frames to said cross conveyor, and a gravity conveyor interposed between said unloading station and said last named conveyor to automatically deliver said empty frames to said last named conveyor.

10. Brick hacking apparatus of the kind described, comprising a set of tracks, a second set of tracks parallel with said first tracks and converging thereon adjacent to its ends, 25 electrically operated carriers on said tracks, means to automatically reverse the direction of movement of said carriers at the end of said first tracks, a loading station in said first tracks, an unloading station remote from 30 said loading station, a plurality of grouping frames, a cross conveyor adapted to carry said frames to said loading station beneath said carriers, means on each of said carriers adapted to clamp a frame therein for transfer to 35 said unloading station, a conveyor adapted to return empty frames to said cross conveyor, and a gravity conveyor interposed between said unloading station and said last named conveyor to automatically deliver said 40 empty frames to said last named conveyor.

11. Brick hacking apparatus of the kind described, comprising a set of tracks, a second set of tracks parallel with said first tracks and converging thereon adjacent to its ends, 45 electrically operated carriers on said tracks, means to automatically reverse the direction of movement of said carriers at the end of said first tracks, a loading station in said first tracks, an unloading station remote from said 50 loading station, a plurality of grouping frames, a cross conveyor adapted to carry said frames to said loading station, means on each of said carriers adapted to clamp a frame therein for transfer to said unloading station, a conveyor adapted to return empty frames to said cross conveyor, said first set of tracks inclining upwardly from said unloading station, and a gravity conveyor interposed between said inclined tracks and said 55 last named conveyor to automatically deliver said empty frames to said last named conveyor.

12. Brick hacking apparatus of the kind described, comprising a set of tracks, a second set of tracks parallel with said first

tracks and converging theron adjacent to its ends, electrically operated carriers on said tracks, means to automatically reverse the direction of movement of said carriers at the end of said first tracks, a loading station in 70 said first tracks, an unloading station remote from said loading station, a rotatably mounted car positioned beneath said unloading station, a set of grouping frames of varying sizes and capacity, a cross conveyor adapted to carry said frames to said loading station, means on each of said carriers adapted to clamp a frame therein for delivery to said unloading station, said frames being conveyed to said unloading station in proper sequence 75 to lay the courses of a complete hack on said car.

13. Brick hacking apparatus of the kind described, comprising a set of tracks, a second set of tracks parallel with said first tracks and converging thereon adjacent to its ends, electrically operated carriers on said tracks, means to automatically reverse the direction of movement of said carriers at the end of said first tracks, a loading station in 80 said first tracks, an unloading station remote from said loading station, a rotatably mounted car positioned beneath said unloading station, a set of grouping frames of varying sizes and capacity, a cross conveyor adapted to carry said frames to said loading station, means on each of said carriers adapted to clamp a frame therein for delivery to 85 said unloading station, said frames being conveyed to said unloading station in proper sequence to lay the courses of a complete hack on said car, and means to automatically return said unloaded carriers to said loading station.

14. In testimony whereof, I have signed my 105 name to this specification.

FRANK C. LAYER.
